(57) **CLAIM**

The ornamental design for a bearing for a yo-yo, as shown and described.

DESCRIPTION

FIG. 1 is a front, top and right perspective view showing a first embodiment of our new design for a bearing for a yo-yo;
FIG. 2 is a front view thereof;
FIG. 3 is a rear view thereof;
FIG. 4 is a left side view thereof;
FIG. 5 is a right side view thereof;
FIG. 6 is a top view thereof;
FIG. 7 is a bottom view thereof;
FIG. 8 is reduced scale front view showing the design in its intended context;
FIG. 9 is a front, top, and right perspective view showing a second embodiment of our new design for a bearing for a yo-yo;

FIG. 10 is a front view thereof;
FIG. 11 is a rear view thereof;
FIG. 12 is a left side view thereof;
FIG. 13 is a right side view thereof;
FIG. 14 is a top view thereof;
FIG. 15 is a bottom view thereof; and,
FIG. 16 is a reduced scale front view showing the second embodiment of the design in its intended context.
The appearance within the unshaded trapezoidal shaped areas in FIGS. 4 and 12 forms no part of the claimed design.
The broken lines showing a cross sectional view of a yo-yo in FIGS. 8 and 16 are for illustrative purposes only and form no part of the claimed design.
